UNITED STATES PATENT OFFICE.

CHARLES A. HERRMANN, OF BATH, NEW YORK, ASSIGNOR TO AMERICAN MULTI-
PLANE COMPANY, INC., A CORPORATION OF NEW YORK.

FLYING-MACHINE.

1,365,995.

Specification of Letters Patent. Patented Jan. 18, 1921.

Application filed October 3, 1916, Serial No. 123,558. Renewed April 26, 1919. Serial No. 293,015.

To all whom it may concern:

Be it known that I, CHARLES A. HERRMANN, a citizen of the United States, residing at Bath, in the county of Steuben and 5 State of New York, have invented new and useful Improvements in Flying-Machines, of which the following is a specification.

My invention pertains to airships, and it has special reference to the disposition or arrangement of the supporting surfaces.

My object is to provide a flying machine with a large supporting surface and at the same time occupying but a comparatively small area, thereby enabling the aviator to 15 handle the machine with the same facility as a small structure, and which shall have a low metacentric point.

A further object is to so arrange the planes that the motive power can be disposed 20 in such a manner that a perfect balance is secured, and which will contribute to the highest efficiency in propelling the craft.

A still further object is to provide a means whereby it may be readily adapted for military uses, as well as commercial purposes, 25 and in which machine guns can be mounted fore and aft and assure a wide range of action for the gunners in all directions.

Owing to the large sustaining surface 30 available by the construction herein shown, it is specially adapted as a freight or passenger carrier, the space in the main longitudinal body, as well as within the parallel side bodies, affording ample room for handling 35 merchandise.

The invention consists in grouping all the planes in a mass so disposed that each will have an effective lift, entirely free from interference with each others' stream lines, 40 which, in effect, enables me to provide a very large surface without a great lateral wing spread. This is brought about by also materially increasing the wing spread in a fore and aft direction, but their disposition is 45 such that the angle of flight is easily handled by the rear control planes, all of which will now be set forth in detail.

In the accompanying drawing Figure 1 is 50 a side elevation of my invention in grouped mass formation for planes, and

Fig. 2 is a plan or top view of my invention.

In carrying out my invention I provide at 55 least three groups of planes, the term group being applied to either a set of bi-planes or

of tri-planes, arranged in tandem-fashion, one group of two planes being followed by a group of three, and so on. The drawings show the preferred form, as I find it to be efficient in practice, although it is obvious 60 that more than the three groups are available. In the present construction the three-plane group, composed of the planes 4, 4, 4, is intermediate the front group of the planes 5, 5, and the rear group of the planes 6, 6. 65

Vertical posts 7, at suitable distances apart serve as supports for the intermediate group, and also support the rear margins of the front group, 5, 5, as well as the anterior margins of the rear group 6, 6. Posts 8 are 70 placed at the forward ends of the first group, and similar posts 9 at the rear ends of the planes 6, 6. Brace members 10, 11, arranged in A-shaped formation, with their apex at the forward post 8, extend down to 75 the wheel skid 12 and similarly-disposed brace members 13, 14, with their upper ends attached to the post 9, have their lower ends also secured to the skids. These, together with the V-shaped brace members 15, 16, 80 which are connected with the lower ends of the posts 7, 7, constitute the fuselage, and in practice the brace members 10, 11, 13, 14, extend down from the posts 8, 9, at a point alongside the two side tubular bodies which 85 carry the propellers, while the V-shaped members 15, 16, are, preferably, extended down from the main central tubular body, or chassis, and also serve to support the posts alongside the two tubular bodies. 90

The fuselage thus constructed is exceedingly strong and rigid, being braced in all directions and admirably adapted to sustain the weight to be carried by the sustaining surfaces. While I show all of the planes the 95 same length, I may modify that feature, making the upper planes longer than the lower ones, but that is immaterial. It is particularly pointed out, however, that half of the supporting surface is in the intermediate 100 group as the three planes are broader, fore and aft, than the front and rear planes.

The object of this construction is two-fold, first, to use the intermediate group as a pivot, and thus enable the aviator to easily 105 and quickly change the angle of flight, and, second, to afford ample space between the planes of the front and rear groups so that the disturbed air from the front planes will not affect the lift of the rear planes. As a 110

- groups embodying a plurality of superimposed planes, and each of the groups in front and in rear of said first named group embodying a less number of planes than said first named group, the planes of each group being out of horizontal alinement with the planes of the adjacent group and said groups of planes constituting substantially the total supporting surface of the machine.
10. 2. In aeroplanes, a plurality of planes, comprising three groups, the intermediate group having a sustaining surface equal to the combined area of the two other groups, and said groups of planes constituting substantially the total supporting surface of the machine, in combination with control planes to the rear of the said grouped planes.
3. In aeroplanes, a plurality of planes, comprising three groups in tandem formation, the planes of the intermediate group being wider fore and aft than the planes of the other groups, in combination with control planes to the rear of said grouped planes.
25. 4. In aeroplanes, a plurality of planes, comprising three groups of planes, the intermediate group having a sustaining surface equal to the combined area of the two other groups and said groups of planes constituting substantially the total supporting surface of the machine, in combination with propellers arranged fore and aft of the said groups, and control planes to the rear of said groups and said propellers.
35. 5. In aeroplanes, a plurality of planes, comprising three groups of planes in tandem

formation, the planes of the intermediate group being wider than the planes of the other groups, in combination with propellers fore and aft of said groups.

6. In aeroplanes, a plurality of planes, comprising three groups, each group embodying a vertical series of superimposed planes in spaced relation to each other the intermediate group having a sustaining surface equal to the combined area of the two other groups, the said three groups constituting substantially the total supporting surface of the machine.

7. In aeroplanes, a plurality of planes, comprising three groups in tandem formation, each group embodying a vertical series of superimposed planes in spaced relation to each other, the planes of the intermediate group being wider fore and aft than the planes of the other groups.

8. In aeroplanes, a plurality of planes comprising three groups, in tandem formation, the intermediate group having a greater number of planes than the front and rear groups and disposed out of horizontal alinement with the planes of said front and rear groups, the said three groups constituting substantially the total supporting surface of the machine, a centrally arranged tractor propeller, and a pair of pusher propellers arranged equidistantly from the center of the machine and at opposite sides of the center of the tractor propeller in the line of flight.

In testimony whereof I affix my signature.

CHARLES A. HERRMANN.
